UNITED STATES PATENT OFFICE

103,572

DESIGN FOR A RADIO CABINET

Philip Holzer, Jr., Chicago, Ill.

Application October 5, 1936, Serial No. 65,165

Term of patent 7 years

To all whom it may concern:

Be it known that I, Philip Holzer, Jr., a citizen of the United States, residing in Chicago, in the county of Cook and State of Illinois, have invented a new, original, and ornamental Design for Radio Cabinets, of which the following is a specification, reference being had to the accompanying drawing, forming part thereof.

The figure is a perspective view of a radio

cabinet, showing my new design. The rear of the cabinet is similar in design, shape and appearance to the front view shown in the figures, except that the various dials are omitted.

I claim:

The ornamental design for a radio cabinet, as shown and described.

PHILIP HOLZER, JR.
